UNITED STATES PATENT OFFICE.

JOHN H. CLASS, OF EXCELSO, OHIO.

SASH-HANGER.

1,150,015.

Specification of Letters Patent. Patented Aug. 17, 1915.

Application filed September 16, 1914. Serial No. 361,924.

To all whom it may concern:

Be it known that I, JOHN H. CLASS, a citizen of the United States, residing at Excello, in the county of Butler and State of Ohio, have invented new and useful Improvements in Sash-Hangers, of which the following is a specification.

This invention relates to new and useful improvements in sash hangers.

10 Many factory, public and other buildings are provided with windows and transoms which, because of their height above the floor and other reasons, are difficult to open and close for ventilating and other purposes.

15 The object of my invention, therefore, is to provide a mechanism for supporting the sash in such a manner that the window may be opened and closed easily and quickly, or entirely removed from the frame with the 20 least possible labor. The mechanism for accomplishing this result is extremely simple, and when attached to two or more windows, all may be opened and closed together from a common point, in the time it takes to operate one.

25 In the accompanying drawings, Figure 1 is a front elevation of a series of windows equipped with my improved sash hanger. Fig. 2 is a section taken on the line $a-a$ of Fig. 1, showing the mechanism for opening and closing said windows. Fig. 3 is a perspective view showing that part of the sash hanger which is attached to the window sash. Fig. 4 is a perspective view of the 30 aforesaid portion of said hanger provided with an operating arm. Fig. 5 is a plan view of that part of the sash hanger which is attached to the window frame. Fig. 6 is a perspective view, showing the operating 35 lever for opening and closing a window or windows, and Fig. 7 is a detail view of the arm attached to one end of the transverse operating shaft.

40 Throughout the specification and drawings, similar reference characters denote corresponding parts.

45 In a detailed description of my invention, 1 designates a trapezoidal plate provided at its upper right hand corner with an outwardly inclined slot 2. Closely adjacent the vertical edge of the plate 1 opposite the slot 2, is a row of apertures 3 adapted to receive screws 4 by means of which said plate is secured to a window frame 5. A plate 1 is 50 secured to one side of the window frame 5 at any desirable point above the sill, while another plate 1 is attached to the other side of said frame immediately opposite the first named one. The plates 1 are so mounted on the frame that a window sash may be readily 55 placed between them, and also in such a manner that their slotted corners will extend well beyond the window frame for a purpose to be hereinafter described. (See Figs. 2 and 5.)

60 Referring to Figs. 3 and 4, the numeral 6 designates a plate similar in outline to the plate 1, but provided with a large headed pin 7 at a point corresponding to that occupied by the bottom of the slot 2 in the plate 1. By means of screws 8, a plate 6 is secured to each side edge of a window sash 9 in such a manner that the pin 7 of each plate will loosely enter and be supported by the slot 2 of the adjoining plate 1 secured to the window frame. Thus said slots 2 will 65 act as bearings for the pins 7 of the plates 6 which support the sash 9, enabling a window 70 whose sash is so supported to be readily opened and closed when desired. It is also possible to entirely remove said window 75 from the frame for cleaning or other purposes; by simply lifting the pins 7 out of the open ends of the slots 2. (See Figs. 1, 2, 3 and 4.)

80 The plates 6 have right angled ears 11 which are secured to the front portions of the sash 9 by means of screws 12. The ear 11 is provided to enable the plate 6 to be more firmly secured to the sash 9, and further, to enable an arm 13 to be secured to or made integral therewith for the following purpose.

85 It is frequently desirable, where a large number of windows are mounted high above the floor of a building, to open and close them together by a single and simple operation. The need of easily opening such windows for ventilation, and quickly closing them in the time of storm, emphasizes the 90 importance of my operating mechanism which may be easily attached to the sash hanger heretofore described, for opening and closing a number of windows in unison. This operating mechanism is adapted to co-operate with the sash hanger, in making the operation of opening and closing the window an easier one than where the operating mechanism is not used, and while it may be used in conjunction with the sash hanger, it 95 is not essential to the operation of the latter. Then again, while the operating mech-

anism hereafter to be described is preferred, any other form of construction for opening and closing windows equipped with my improved sash hanger may be employed if desired.

In Fig. 1 there is shown a number of windows supported high above the floor by my improved sash hanger, and adapted to be opened and closed in unison by the following described mechanism which I prefer for that purpose.

Referring to Figs. 1 and 2, it will be observed that one of each pair of plates 6 is provided with an arm 13 adapted to loosely receive through an aperture 14, the turned end 15 of a connecting rod 16. The end 15 of said rod is threaded to receive a nut 17 provided for the purpose of holding said end within the aperture 14 during the movement of the arm 13.

The rod 16 has a hook end 18 which is loosely received by an aperture 19 in an arm 20 fast on a shaft 21, the latter being journaled in bearings 22 and 23 suitably mounted a short distance below the windows 10. (See Figs. 1 and 2). One end of the shaft 21 extends through the bearing 23, and to the extended end of said shaft is attached an arm 24 which loosely receives through an aperture 25, the hook end 26 of a rod 27.

(See Figs. 1, 2 and 7). The rod 27 in turn has a bent threaded end 28 which loosely passes through an aperture 29 in an operating lever 30; a nut 31 being applied to said threaded end to hold it within the aperture 29 during the movement of the lever 30. This lever is mounted on a pivot 32 secured to the projecting portion 33 of a bracket 34. The attachable portion of said bracket consists of a rectangular plate 35 which, by means of screws 36 adapted to pass through apertures 37, may be secured to the wall at any point which will make the lever 30 readily accessible to the operator. (See Figs. 1, 2 and 6.)

The projecting portion 33 of the bracket 34 consists of a plate which is preferably at right angles to and integral with the plate 35, but instead of being rectangular, said plate has a curved outer edge 39 adjacent to which is an arcuate row of apertures 40, any one of which is adapted to register with an aperture 41 within the lever 30. Accordingly, whenever the lever 30 is moved to a position to bring its aperture 41 directly over an aperture 40, a pin 42 may be forced through said registering apertures to hold the lever 30 in its adjusted position. A suitable restraining guide for the lever 30

during its movement, is provided in the form of a bar 43 mounted above said lever 60 upon posts 44 secured to the plate 33. It will now be seen that when the lever 30 is moved downwardly, it will draw with it the rod 27 to turn the shaft 21 through the arm 24; and when said shaft is turned, the arms 20, through the rods 16, will exert a downward pull on the arms 13, which will in turn swing the windows 10 outwardly about the fulcrums formed by the slots 2 in the plates 1. When the lever 30 is moved upwardly, the movement of the mechanism just described will be reversed to close said windows.

The operation of my improved sash hanger has already been explained in the foregoing description, as well as the operation of the mechanism to be used in conjunction with said hanger for opening or closing one or more windows at a distance. Its advantages may be summed up in the statement, that where my hanger is employed, a window sash may be easily and quickly swung outwardly and inwardly by reason of the slot and pin connection between the plates 1 and 6; or, by lifting the pins 7 out of the slots 2, the sash may be entirely removed from the frame for cleaning or other purposes. Then to replace the sash within the window frame is only a matter of reinserting the pins 7 within the slots 2, after which the window may be readily opened and closed with or without the operating mechanism heretofore described.

I do not wish to be limited to the details of construction and arrangement herein shown and described, and any changes or modifications may be made therein within the scope of the subjoined claim.

Having described my invention, I claim:

In a sash hanger, a fixed plate provided with an inclined bearing slot, a movable plate integral with and projecting from a right-angled portion adapted to be secured to a sash, a large-headed pivot extending outwardly from the movable plate, to enter said bearing slot, and an operating arm integral with, and extending rearwardly from the sash attaching portion of the movable plate, substantially as described.

In testimony whereof I have hereunto set my hand this 14th day of September, 1914.

JOHN H. CLASS.
